KNITTING MACHINE

Clyde N. Stover, Baltimore, Md., assignor to
Western Electric Company, Incorporated, New
York, N. Y., a corporation of New York

Application July 9, 1938, Serial No. 218,301

13 Claims. (Cl. 66—9)

This invention relates to knitting machines and more particularly to knitting machines for applying a knitted covering over a core such as an electrical conductor.

In high speed knitting machines one of the limiting factors in speed is needle breakage, and this is greatly affected by the slope of the cam lobes by which the needles are reciprocated.

An object of the present invention is to provide an effective and efficient high speed knitting machine.

In accordance with one embodiment of the invention a knitting machine is provided having a rotating cylinder and a rotating cam having fewer cam lobes than thread supplies, the relative speeds of rotation of the cam and needle cylinder being so correlated that the rotating cam actuates the needles in the rotating cylinder in a predetermined relation to stationary thread supplies.

Other objects and advantages will appear as the description proceeds.

A complete understanding of the invention may be had by reference to the following description taken in conjunction with the accompanying drawings, in which

Fig. 1 is a sectional view of a knitting machine embodying the invention;

Fig. 2 is a schematic illustration of the relationship between the thread supplies, needles and cam lobes;

Fig. 3 is a plan view of a cam for actuating the needles;

Fig. 4 is a view partly in section taken on lines 4—4 of Fig. 3;

Fig. 5 is a sectional view taken on lines 5—5 of Fig. 4; and

Fig. 6 is a plane development showing one pattern of knitted structure made with the apparatus of this invention.

Referring now more in detail to the figures, and particularly to Fig. 1, the apparatus is shown as mounted in a housing 11 having two upwardly extending standards 12, which carry a cross piece 13 supporting a tubular member 14, through which a core such as an electric conductor to be covered with a knitted tubular covering is passed. Attached to the downwardly projecting portion of the tube 14 is a disk 15 which supports a plurality of adjustable thread guides 16, each of which is provided with an eyelet in its lower end through which a thread from one of the several thread supplies is guided to the knitting head. The threads passing through the thread guides are withdrawn from station-

ary cops (not shown) from which the threads are removed over one end of the cops without rotating the cops, as is well known in the art.

Mounted in the housing 11 is a needle bed or cylinder 17 having radial slots 18 cut therein in which needles 19 are adapted to reciprocate. The upper ends of the needles are held onto the needle cylinder by a disk 21 made in two sections and secured in place by nut 22. The needle cylinder 17 is mounted on a cylindrical support 23 having a pair of diametrically opposite slots 24 which coincide with similar slots on the lower portion of the needle cylinder, and keys 25 are placed in these slots to permit the needle cylinder to move longitudinally with respect to the support 23, but relative rotational movement is prevented by the keys. The lower end of the needle cylinder is threaded and a sleeve 26 is inserted into the lower end of the cylinder support

23 and is threaded onto the needle cylinder. A lock nut 27 is threaded into the lower end of the cylinder support and engages the sleeve 26 to retain the sleeve in position. In order to adjust the needle cylinder up and down relative to the needles the lock nut 27 is loosened and the sleeve 26 is rotated in one direction or the other to adjust the needle cylinder. When the needle cylinder is in its proper position the lock nut 27 is tightened to hold it in that position. The purpose of adjusting the needle cylinder with respect to the needles is to selectively determine the distance that the needles move below the upper rim of the needle cylinder. For instance, in knitting a covering on a conductor the conductor is drawn through the knitting machine at such a speed as to form a predetermined number of knitted loops per foot of conductor. If the loops thus formed are too tight, the needle cylinder is adjusted upwardly to increase the distance that the needles travel below the upper rim of the needle cylinder to loosen the loops.

Surrounding the needle cylinder is a cam housing 28 supported upon a cylindrical cam support 29. The needle cylinder and the needle support are journaled in ball bearings 31 and 32 in the cam support 29, and the entire rotating mechanism is supported in a ball bearing 33 mounted in the lower portion of the housing 11 and a bearing 34 in the upper portion of the housing.

Within the cam housing 28 is a lower cam section 35 which fits into the cam housing, and ro-

tation relative to the cam housing is prevented by a key 36. The upper cam section 37 is spaced from the lower cam section to form a groove into which the butts 20 of the needles project by a ring 38 which fits snugly within the cam housing. The upper cam section is similarly held against rotation relative to the cam housing by a key 39. In order to hold the several sections of the cam in place an internally threaded annular ring 41 is threaded onto the cam housing 28.

In operating a knitting machine it is frequently necessary to change one or more of the needles which become broken or defective, and it is desirable to be able to replace one or more of the needles without removing the entire needle cylinder from the apparatus. For this purpose a slot is formed in the upper cam section, and a key 42 which normally closes the slot is placed in the slot. This key has a sloping portion 43 which corresponds to the slope of the cam groove at this point. Thus when it is desired to remove a needle the nut 22 and disk 21 are removed from the upper end of the cylinder; then the annular ring 41 is removed, which permits the key 42 to be withdrawn from the slot. The cylinder may then be rotated relative to the cam so that any one of the needles is in alignment with the slot and may be withdrawn upwardly from the needle cylinder without removing the needle cylinder from the machine.

It is preferable to place the slot through which the needles are drawn on the leading slope of a cam lobe in the direction of rotation of the cam. Referring to Fig. 5, if it is assumed that the portion of the cam having the slot therein moves from left to right, it will be noted that the butt of the needle will ride on the lower side of the cam slot while the needle removing slot is on the upper side of the cam slot. By thus arranging these parts it has been found that the key 42 may be omitted from the slot without interfering with the operation of the needles.

The cam support 29 may have a beveled gear 44 integral therewith, and the cylinder support 23 may have a beveled gear 45 secured thereto. Co-operating gears 46 and 47 are mounted on a drive shaft 48 and, in the particular embodiment of the invention illustrated, the cam is rotated at three times the speed of the needle cylinder 50 and in the same direction.

In the ordinary knitting machine in which there is no relative rotation between the cam and the thread supplies, it is necessary to have as many cam lobes as there are thread supplies, as the result of which the cam lobes must be spaced very closely together, and therefore the slope or pitch of the cam lobes must be very high. The result is that a high lateral pressure is exerted upon the needle butts, resulting in a high needle breakage, particularly when the machines are operated at high speeds.

Fig. 2 illustrates a practical embodiment of the present invention in which there are only one-half as many cam lobes as there are thread supplies. In Fig. 2 the thread supplies are indicated by reference numerals T¹, T², T³, etc., while the high points of the cam lobes are designated by C¹, C², C³, etc. The needles are indicated by N¹, N², N³, etc. The needles in this embodiment rotate with the needle cylinder in a clockwise direction, and the cam rotates at three times the speed of the needle cylinder, also in a clockwise direction. Thus it will be seen that cam lobe C¹ has caused needle N¹ to engage thread supply T¹.

By the time that needle N¹ reaches thread supply T² cam lobe C⁶ will cause needle N¹ to engage thread supply T². The pattern made with the given number of thread supplies, needles and cam lobes is shown in Fig. 6, in which the needles are shown on the ordinate axis and the thread supplies on the abscissa axis.

It will be noted that in the illustration shown in Fig. 2 the number of thread supplies plus the number of cam lobes is equal to the number of needles. This may be expressed as T+C=N where T is the number of thread supplies, C the number of cam lobes, and N the number of needles. With this relationship the ratio of the speed of the cam relative to the cylinder must be equal to the number of needles divided by the number of cam lobes. This may be expressed in the following equation:

$$S = \frac{N}{C}$$

where N is the number of needles, C the number of cam lobes and S the ratio of the cam to the cylinder speed. This relationship also holds true if the cam is driven in the opposite direction to that of the cylinder, in which case the number of cam lobes C must be considered a negative quantity.

Thus the following combinations based upon the above relationships may be employed:

- 30 8 thread supplies, 4 cam lobes, 12 needles, rotating the cam 3 times the speed of the needle cylinder and in the same direction.
- 35 8 thread supplies, 8 cam lobes, 16 needles, rotating the cam 2 times the speed of the needle cylinder and in the same direction.
- 40 10 thread supplies, 5 cam lobes, 15 needles, rotating the cam 3 times the speed of the needle cylinder and in the same direction.
- 45 4 thread supplies, 2 cam lobes, 6 needles, rotating the cam 3 times the speed of the needle cylinder and in the same direction.

The following is an illustration of rotating the cam and cylinder in opposite directions:

- 50 6 thread supplies, 2 cam lobes, 4 needles, rotating the cam 2 times the speed of the needle cylinder and in the opposite direction.

The term "stationary thread supplies" is used in the specification and appended claims to signify that the thread supplies do not rotate about the core being covered.

It will be understood that the nature and embodiment of the invention herein disclosed is merely illustrative and that many changes and modifications may be made therein without departing from the spirit and scope of the invention.

What is claimed is:

1. In a knitting machine, a housing, a cam, a cylindrical support for the cam journaled in one end of the housing, a needle cylinder, a cylindrical support for the needle cylinder journaled in the cam support and projecting therethrough, the projecting end of the cylinder support being journaled in the other end of the housing, and means for rotating both the cam support and cylinder support.

2. In a knitting machine, a frame, a cam having a cylindrical cam support journaled externally in said frame and having a pair of internal bearings, a needle cylinder having a cylindrical support journaled in said internal bearings of the cam support and projecting therethrough,

said projecting end of the needle cylinder support being journalled in said frame, and means for rotating both the cam support and needle support.

3. In a knitting machine having a needle cylinder provided with reciprocating needles, cam means for actuating the needles comprising a cam housing, a pair of cam sections forming a cam, one of said cam sections having a cut-out portion in its outer periphery, a ring in said cut-out portion of said cam section for spacing the cam sections to form a cam groove, and means for securing said cam sections and ring in the cam housing.

4. A knitting machine comprising a rotatable needle cylinder having reciprocable needles mounted thereon, a plurality of thread supplies, a rotatable cam having cam lobes, the number of cam lobes plus the number of thread supplies being equal to the number of needles, and means for rotating the cam at three times the speed of the needle cylinder and in the same direction.

5. A knitting machine comprising a rotatable needle cylinder having reciprocable needles mounted thereon, a plurality of thread supplies, a rotatable cam having cam lobes, the number of cam lobes plus the number of thread supplies being equal to the number of needles, and means for rotating the cam

$$\frac{N}{C}$$

times as fast as the cylinder, where N is the number of needles and C the number of cam lobes

6. A knitting machine comprising a rotatable needle cylinder having reciprocable needles mounted thereon, a plurality of thread supplies, a rotatable cam having cam lobes, and means for rotating the cam

$$\frac{N}{C}$$

times as fast as the cylinder, where N is the number of needles and C the number of cam lobes.

7. A knitting machine comprising a rotatable needle cylinder having reciprocable needles mounted thereon, a plurality of stationary thread supplies, and a rotatable cam having cam lobes, the algebraic sum of the number of thread supplies plus the number of cam lobes being equal to the number of needles.

8. A knitting machine comprising a rotatable needle cylinder having reciprocable needles mounted therein, a plurality of stationary thread supplies, and a rotatable cylindrical cam having lobes forming a groove engaged by the needles to

actuate the needles, the number of cam lobes being less than the number of thread supplies.

9. A knitting machine comprising a rotatable needle cylinder, a plurality of needles mounted in the cylinder, a rotatable cylindrical cam concentric with said cylinder having cam lobes forming a groove for actuating the needles, and stationary thread supplies, the number of cam lobes being less than the number of thread supplies.

10. A knitting machine for applying a knitted covering to a core, comprising a plurality of thread supplies, a rotating needle cylinder provided with knitting needles, and rotating cam means for actuating said needles to operate upon selected ones of the stationary thread supplies, all of the thread supplies of the machine being stationary so that all knitted ribs of the product of the machine lie in the product in straight lines parallel to the axis thereof.

11. A knitting machine for applying a knitted covering to a core, comprising a rotating needle cylinder having reciprocable needles mounted thereon, thread supply means for supplying thread to a plurality of positions about said cylinder, and rotating cam means for actuating said needles in predetermined relation to said thread supply positions, all of the thread positions of the machine being stationary so that all knitted ribs of the product of the machine lie in the product in straight lines parallel to the axis thereof.

12. A knitting machine for applying a knitted covering to a core, comprising a rotating needle cylinder having reciprocable knitting needles mounted thereon, a plurality of thread supplies, thread guides disposed about said cylinder to receive threads from the thread supplies, and rotating cam means for actuating said needles in predetermined relation to threads carried by said guides, all of the thread guides of the machine being stationary so that all knitted ribs of the product of the machine lie in the product in straight lines parallel to the axis thereof.

13. A knitting machine comprising a plurality of thread supplies, a rotating needle cylinder, needles mounted in said cylinder, a cam associated with said needles, and means causing said needles to reciprocate in predetermined relationship to the thread supplies by the rotation of both the needle cylinder and cam relative to the thread supplies, all of the thread supplies of the machine being stationary so that all knitted ribs of the product of the machine lie in the product in straight lines parallel to the axis thereof.

CLYDE N. STOVER.
